VALVE OPERATING MECHANISM

Henry J. Hanzlik, Swarthmore, Pa., assignor to
Westinghouse Electric & Manufacturing Company, East Pittsburgh, Pa., a corporation of Pennsylvania

Application March 21, 1934, Serial No. 716,673

9 Claims. (Cl. 60—97)

My invention relates to valve operating mechanism for controlling elastic fluid prime movers, and it has for a broad object to provide apparatus of this character which is of improved construction, is compact, and is simple.

According to one aspect of my invention, I provide a valve operating mechanism which is especially adapted to control an elastic fluid prime mover of the type having both ahead and astern sections; or to control two separate prime movers, wherein one is used for ahead operation and the other for astern operation. The improved mechanism comprises a single control element which may be moved to effect either ahead or astern operation, as desired.

According to another aspect of my invention, I provide a control mechanism for elastic fluid prime movers used for the propulsion of ships wherein equal increments of movement of a control element provide equal changes in the speed of the ship.

These and other objects will be effected by my invention as will be apparent from the following description and claims taken in connection with the accompanying drawings forming a part of this application, in which:

Fig. 1 is a side elevation showing my invention as applied to an elastic fluid turbine having ahead and astern sections;

Fig. 2 is an enlarged vertical section through one of the valves and its operating relay shown in Fig. 1;

Fig. 3 is a diagrammatic view showing the shape of the cam used in the relays which transmits the force applied by the control member to the relay and the main steam valve;

Fig. 4 is a plan view on a reduced scale showing the turbine of Fig. 1 as driving a ship's propeller through a reduction gear unit;

Fig. 5 is a graph showing the amount of steam flow required for the speed range of a ship;

Fig. 6 is a graph showing the amount of valve lift required for securing the range of steam flow or horsepower in the conventional type of plug or poppet valve;

Fig. 7 is a graph showing the amount of valve lift required for the speed range of a ship wherein a steam valve of the conventional plug type is used; and

Fig. 8 is a view similar to Fig. 1 showing a modified form of valve operating mechanism.

Referring now in detail to the construction illustrated, and particularly to Figs. 1 to 7, inclusive, it will be observed that I have shown my invention as applied to a steam-motivated tur-

bine 10 having an ahead section 11 and an astern section 12, and including a shaft 13 which is connected by a suitable coupling 14 to a reduction gear unit 15, and the latter is in turn connected to a shaft 16 of a ship propeller 17 (see Figs. 1 and 4).

A steam pipe 18 serves to convey motive steam to first and second conduits 19 and 20 and the latter are connected, respectively, to the ahead and astern sections 11 and 12. First and second steam valves 21 and 22 are disposed in the conduits 19 and 20, respectively, and serve to regulate the flow of steam to the ahead and astern sections. The valves 21 and 22 are operated respectively by first and second oil-operated relays 23 and 24.

As the detail construction of the steam valve 21 and its oil-operated relay 23 is the same as the steam valve 22 and its oil-operated relay 24, I have shown in detail and will describe only the valve 21 and the relay 23 (see Fig. 2).

The valve 21 is disposed within a valve casing 25 and is provided with an operating stem 26 which extends exteriorly of the casing 25 and is connected by a coupling 27 with an operating rod 28 of the relay 23. In order to prevent fires caused by oil leaking from the relay onto the hot steam pipes, the relay 23 is disposed beneath the valve casing 25 and is connected thereto by means of steel rods 29, each of the rods being 30 screwed at one end, as indicated at 30, into the relay 23 and is welded at its other end to the valve casing 25.

The relay 23 includes a secondary element 31 operatively connected to the steam valve 21, as 35 will presently appear, and is movable in response to an operating force, for example, oil under pressure, for opening and closing the valve. The relay also includes a primary element 32 movable to control the application of the operating 40 force to the secondary element 31 and a follow-up lever 33, one purpose of which is to return the primary element to neutral position upon movement of the steam valve 21 in either direction.

The secondary element 31 comprises an operating cylinder 34, an operating piston 35, the previously described rod 28 connecting the piston 35 and the valve stem 26, and one or more compression springs 36 disposed between the upper end of the cylinder 34 and the piston 35 and exerting a force in opposition to the force of the operating oil and in a direction to close the steam valve. A passage 37 serves to convey the 55

operating oil under pressure to and from the lower end of the cylinder.

The primary element 32 comprises a cylinder 40 and a pilot valve 41. The cylinder 40 is provided with spaced-annular ports 42, 43, 44, 45, and 46. The port 42 is in communication with the passage 37. The port 43 is in communication with a pipe 47 which provides operating oil under pressure from any suitable source (not shown). The port 44 communicates through an opening 48 in the upper end of the operating cylinder with an opening 49 in the cylinder and a pipe 50 connected to any suitable place of discharge. The port 45 is connected to a pipe 51 which serves to convey governing oil under pressure from a governor pump 52 of the impeller type driven by the turbine shaft 13. The port 46 serves to conduct leakage oil to the cylinder 34 and drainage pipe 50.

The pilot valve 41 fits within the cylinder 40 and comprises a valve portion 55 and a pusher or tappet portion 56 connected to the valve portion by means of a tension spring 57 and a rod 58, which latter serves to hold apart the valve portion 55 and pusher portion 56 and thereby provide for an initial tension on the spring 57. The rod 58 abuts at its upper end the pusher portion 56 and the lower end thereof is screw-threaded and extends through a screw-threaded opening 59 in the end of the valve portion 55. The amount of initial tension on the spring 57 may be varied by screwing the rod 58 inwardly or outwardly, as desired.

The valve portion 55 is provided with two spaced annular recesses 60 and 61 separated by a piston portion 62. The piston portion 62 serves to blank off the port 42 and passage 37 leading to the operating cylinder, when the pilot valve is in its neutral or cut-off position. When the pilot valve is moved upwardly from the position shown in Fig. 2, the recess 60 connects the ports 43 and 42 and the operating oil under pressure will flow from the pipe 47 through the ports 43 and 42 and passage 37 to the lower end of the cylinder 34. The oil under pressure will exert a force against the lower side of the piston 35 sufficient to move the piston upwardly against the spring 36 and open the steam valve 21. When the pilot valve is moved downwardly from the neutral position shown, the recess 61 will connect the ports 42 and 44 and the operating oil will flow out of the lower portion of the cylinder 34 through the passage 37, ports 42 and 44, opening 48, and upper portion of the cylinder 34 to the discharge opening 49 and pipe 50, thereby permitting the spring 36 to move the piston 35 downwardly in a direction to close the steam valve.

The follow-up lever 33 has formed thereon a longitudinally disposed curved slot 64 including an effective cam portion 65 and an ineffective portion 66, the purpose of which will presently appear. A fulcrum element 67 is movable in the slot 64 and is carried by the outer end of a lever arm 68, the other end of the latter being fixed to a rotatable shaft 69 carried by the cylinder 34 of the secondary element. One end of the follow-up lever is pivotally connected by a pin 70 to the upper end of the pusher element 56 of the pilot valve. The other end of the follow-up lever is pivotally connected to the coupling 27. This latter pivotal connection comprises a roller 71 mounted on a pin 72 carried by the lever 33 and engaging an annular flange 73 on the coupling 27 and held against such

flange by means of a spring 74 which is connected at one end to the lever 33 and the other end to the valve casing 25.

As stated previously, one purpose of the follow-up lever 33 is to return the pilot valve to neutral position upon movement of the main valve in either direction. This will be apparent from examination of Fig. 2. Should the pilot valve be moved upwardly to admit the operating oil beneath the piston 35 and thereby move the steam valve 21 in an opening direction, such movement of the steam valve will cause the follow-up lever to rock about its fulcrum element 67 and move the pilot valve back to neutral position. On the other hand, should the pilot valve be moved downwardly from the position shown to discharge the operating oil from beneath the operating piston and thereby move the steam valve in a closing direction if the latter should be open, the follow-up lever will rock about its fulcrum element 67 and move the pilot valve back to its neutral position.

A further and important function of the follow-up lever 33 is to provide for a controlled movement of the pilot valve so as to effect the operation of the secondary element to open and close the valve 21 and control the speed of the turbine. In the drawings, I have shown the force for effecting movement of the pilot valve as being applied by a fulcrum element 67 which is movable along the slot 64 in the lever. The slot 64 is so designed that movement of the fulcrum element from the middle position shown in Fig. 2 to the left and along the effective portion 65 thereof, will result in an upward movement of the pilot valve and the application of the operating oil under pressure beneath the operating piston 35. Movement of the fulcrum element to the right of the position, shown in the drawing and in the ineffective portion 66 will have no effect on the movement of the pilot valve.

Movement of the primary element by the fulcrum element and follow-up lever is due to the design of the effective portion 65 of the slot 64. The sides of the effective portion 65 of the slot are in effect cam surfaces which curve away from the arc of movement of the axis of the fulcrum element. Fig. 3 is a diagrammatic view showing in full lines the center line —a— of the slot with the effective and ineffective portions 65 and 66 indicated thereon. It will be observed that the portion of the center line corresponding to the effective portion 65 of the slot is curved away from a dotted line —b— which indicates the arc of movement of the axis of the fulcrum element. The dotted line —b— does not appear on that portion of the center line which corresponds to the ineffective portions 66 of the slot as the arc of movement of the axis of the fulcrum element is coincident with the center line of the slot at the right of the view.

The relay mechanism is constructed and arranged so that opening of a valve occurs between, for example, the five degree and thirty-five degree positions indicated in Fig. 3, thereby leaving at the middle portions of the cam groove an arc of ten degrees during which both the ahead and astern valves are closed, the reason for this being that the fulcrum may be operated by remote control mechanism involving levers and links and a certain amount of lee-way should be allowed on account of back-lash, mal-adjustment, et cetera, to assure that both steam valves may be closed at an intermediate position

of the operating member or at least that both should a steam valve be used which has a valves shall not be open at the same time. If a straight line characteristic, that is, one wherein the control member or lever is located adjacent to the steam flow, is proportional to the area of to the relays, as shown on the drawings, a much the valve passage, the curve of Fig. 7 would then 5 less intermediate range than ten degrees may approximate the curve of Fig. 5. However, I be provided for this purpose, for example, as have chosen to show on the drawings a conven- range of three or four degrees might be satis- tional type of plug valve, and the cam surface factory. is designed to take care of the operating char-

Referring to Fig. 3, and assuming that the characteristic of such a valve. The fulcrum is at the middle position of the arc. The effective or cam portion 65 of the curved slot 64 is so designed as to compensate for the of the fulcrum for five degrees in a counter-clockwise direction would be necessary to start in Fig. 7 from a straight line function. There- the admission of oil beneath the operating piston; with such a cam as I have shown, the 15 ton 35 to begin opening of the steam valve. The amount of movement of the fulcrum element will 10 like manner, movement would be required for be proportional to changes in the speed of the five degrees of the fulcrum in a clockwise direction. It will be observed from examination of Fig. 1 15 This five degree motion is afforded by the over- that the position of the relay 24 is reversed with 20 lap condition existing between the piston por- respect to the position of the relay 23, that is to 25 tion 62 and the lower edge of the port 42. The say, the relay 24 is arranged with its primary maximum of such overlap, for the cam of Fig. 3, occurs when the fulcrum is at the clockwise and its follow-up lever 33a extending from the five degree position and it is sufficient to pre- steam valve toward the right. Also, the cam 25 vent flow of fluid under pressure from the port portion 65a of the slot 64a is at the left of the 43 to the port 42 until the five degree clockwise mid or neutral position of the fulcrum element position is reached. Thereafter, the steam 67a. The fulcrum element 67a is connected to valve is opened more and more as the fulcrum the outer end of a lever arm 68a which is in turn 30 is advanced in a counter-clockwise direction, fixed to a shaft 69a carried by the relay 24. The

The apparatus is constructed and arranged so that the ahead steam valve or the astern steam 75 which is connected by means of a link 76 valve, as the case may be, is fully opened before the fulcrum reaches the end of the arcuate slot 69. A hand-controlled operating lever 78 is pro- so that steps 78a may be arranged for coopera- 35 tion with the fulcrum or its moving mechanism to limit motion of the fulcrum to such an extent as is necessary to secure opening of either valve 40 45

to wide-open position, whereby it is assured that either valve may be opened fully without the fulcrum abutting the end of the slot and there- 40 by subjecting the lever 33 and rather delicate parts associated therewith, to the impact of the operating mechanism, which in practice may be 45 operated rather rapidly.

The effective or cam portion 65 of the slot 64 is so designed that for equal increments of movement of the fulcrum element, the relay will operate the steam valve to effect equal changes in the speed of the ship. In designing the cam portion of the slot, two characteristics have to be considered, one being that the resistance offered to the movement of the ship through water varies as the cube of the speed of the ship, and the other being the valve lift steam flow characteristic of the particular valve used. In Fig. 5 of the drawings, I have shown a graph which illustrates the horsepower developed on the amount of steam required for the changes in speed of the ship. The curve illustrates the characteristic of the resistance offered to the movement of the ship through water being proportional to the cube of the speed of the ship. In Fig. 6 of the drawings, I have shown a graph which illustrates the steam flow valve lift characteristic of the valve shown, that is, the curve illustrates the amount of steam which flows by the conventional type of plug or poppet valve for the varying area of valve passage pro- 60 vided as the valve moves away from and toward its seat. Fig. 7 of the drawings shows a curve which illustrates the amount of valve lift or area of the valve passage, required to effect the various speeds of the ship. The curve shown in Fig. 7 is derived from the two characteristics illus- 65 trated by the curves shown in Figs. 5 and 6.

Should a steam valve be used which has a valves shall not be open at the same time. If a straight line characteristic, that is, one wherein the control member or lever is located adjacent to the steam flow, is proportional to the area of to the relays, as shown on the drawings, a much the valve passage, the curve of Fig. 7 would then 5 less intermediate range than ten degrees may approximate the curve of Fig. 5. However, I be provided for this purpose, for example, as have chosen to show on the drawings a conven- range of three or four degrees might be satis- tional type of plug valve, and the cam surface factory. is designed to take care of the operating char-

Referring to Fig. 3, and assuming that the characteristic of such a valve. The fulcrum is at the middle position of the arc. The effective or cam portion 65 of the curved slot 64 is so designed as to compensate for the of the fulcrum for five degrees in a counter-clockwise direction would be necessary to start in Fig. 7 from a straight line function. There- the admission of oil beneath the operating piston; with such a cam as I have shown, the 15 ton 35 to begin opening of the steam valve. The amount of movement of the fulcrum element will 10 like manner, movement would be required for be proportional to changes in the speed of the five degrees of the fulcrum in a clockwise direction. It will be observed from examination of Fig. 1 15 This five degree motion is afforded by the over- that the position of the relay 24 is reversed with 20 lap condition existing between the piston por- respect to the position of the relay 23, that is to 25 tion 62 and the lower edge of the port 42. The say, the relay 24 is arranged with its primary maximum of such overlap, for the cam of Fig. 3, occurs when the fulcrum is at the clockwise and its follow-up lever 33a extending from the five degree position and it is sufficient to pre- steam valve toward the right. Also, the cam 25 vent flow of fluid under pressure from the port portion 65a of the slot 64a is at the left of the 43 to the port 42 until the five degree clockwise mid or neutral position of the fulcrum element position is reached. Thereafter, the steam 67a. The fulcrum element 67a is connected to valve is opened more and more as the fulcrum the outer end of a lever arm 68a which is in turn 30 is advanced in a counter-clockwise direction, fixed to a shaft 69a carried by the relay 24. The

The apparatus is constructed and arranged so that the ahead steam valve or the astern steam 75 which is connected by means of a link 76 valve, as the case may be, is fully opened before the fulcrum reaches the end of the arcuate slot 69. A hand-controlled operating lever 78 is pro- so that steps 78a may be arranged for coopera- 35 tion with the fulcrum or its moving mechanism to limit motion of the fulcrum to such an extent as is necessary to secure opening of either valve 40 45

to wide-open position, whereby it is assured that either valve may be opened fully without the fulcrum abutting the end of the slot and there- 40 by subjecting the lever 33 and rather delicate parts associated therewith, to the impact of the operating mechanism, which in practice may be 45 operated rather rapidly.

The effective or cam portion 65 of the slot 64 is so designed that for equal increments of movement of the fulcrum element, the relay will operate the steam valve to effect equal changes in the speed of the ship. In designing the cam portion of the slot, two characteristics have to be considered, one being that the resistance offered to the movement of the ship through water varies as the cube of the speed of the ship, and the other being the valve lift steam flow characteristic of the particular valve used. In Fig. 5 of the drawings, I have shown a graph which illustrates the horsepower developed on the amount of steam required for the changes in speed of the ship. The curve illustrates the characteristic of the resistance offered to the movement of the ship through water being proportional to the cube of the speed of the ship. In Fig. 6 of the drawings, I have shown a graph which illustrates the steam flow valve lift characteristic of the valve shown, that is, the curve illustrates the amount of steam which flows by the conventional type of plug or poppet valve for the varying area of valve passage pro- 60 vided as the valve moves away from and toward its seat. Fig. 7 of the drawings shows a curve which illustrates the amount of valve lift or area of the valve passage, required to effect the various speeds of the ship. The curve shown in Fig. 7 is derived from the two characteristics illus- 65 trated by the curves shown in Figs. 5 and 6.

As the governor pump 52 is driven by the turbine shaft 13, the pressure of the oil in pipe 51 and also the oil bearing against the inner face, or the upwardly facing piston area, of the valve portion 55 of the pilot valve varies as a function of the speed of the prime mover. The tension spring 57 opposes the pressure of the governing oil with a force depending upon the adjustment of rod 58. When the speed of the prime mover exceeds a value where the resulting governing oil pressure is greater than the setting of the spring 57, the oil pressure acting on the upwardly facing piston area of the valve portion 55 will move the valve portion 55 downwardly until the recess 61 connects ports 42 and 44, thereby providing for the discharge of operating oil from beneath the face 70 of piston 35 and permitting the spring 36 to 75

move the piston downwardly and close the steam valve sufficiently to lower the speed of the turbine to a value where the resulting governing oil pressure force does not exceed that of the 5 spring 57 for the setting of the latter.

As stated previously, the initial tension on the spring 57 may be varied to any desired amount by simply adjusting the rod 58. The spring may be adjusted so that the governing oil pressure 10 be used only for preventing over-speeds of the turbine; that is, the turbine will be directly controlled throughout its speed range by the lever 78 acting simply as a throttle, and the governing oil pressure will affect the operation of the 15 apparatus only when the speed of the turbine exceeds a predetermined value which is above the operating range. On the other hand, the spring 57 may be adjusted for some lower speed in the operating range. With the latter adjustment, the lever will serve as a straight throttle 20 until the speed of the turbine reaches the predetermined minimum corresponding to the initial setting of the spring 57, and, for speeds 25 above the predetermined minimum, movement of the lever 78 will result in changing the speed setting of the governor.

The apparatus described provides a simple and effective means for controlling by a single means the operation of prime movers designed 30 for ahead and astern operation, and insofar as this aspect of the invention is concerned, it is not limited in its application to controlling prime movers used as a ship propelling means for it may be used in other connections, for 35 example, for controlling the forward and reversing sections of prime movers used in dipper dredges and the like.

Furthermore, as the purpose of cam 64 is to provide a control wherein the increments of 40 movement of the control or throttle lever correspond to equal changes in the speed of the ship, the cam feature may be applied to any prime mover used for ship propulsion and this is true even though the prime mover be used solely for 45 ahead motion or solely for astern motion.

In Fig. 8, I have shown a form of my invention which is similar in all respects to the construction shown in Figs. 1 to 7, inclusive, with the exception that a modified form of follow-up lever and a control lever is provided.

In Fig. 8, I provide a turbine 100 having an ahead section 101 and an astern section 102; valves 103 and 104 controlling the flow of steam to the ahead and astern sections respectively; and relays 105 and 106 for operating the valves 103 and 104 respectively. The relay 105 comprises a secondary element 107, a primary element 108 and a follow-up lever 109 pivotally connected at one end to the valve stem and pivotally connected intermediate its ends by a pin 110 with the primary element. A longitudinally-disposed, slot 111 is provided in the outer end of the lever 109 and is provided with an effective or cam portion 112 and an ineffective portion 113. The cam portion 112 is designed to operate in the same manner as the cam portion 65 of the previously described modification. Likewise, the relay 106 comprises a secondary element 107a, a primary element 108a, and a follow-up lever 109a having a slot 111a in its end including a cam portion 112a and an ineffective portion 113a. The end carrying the slot 111a overlaps the end of the lever 109 carrying the slot 111. A fulcrum element 114 is provided which is of sufficient width to move within

both slots 111 and 111a. The fulcrum element 114 is carried by the outer end of a lever arm 115 fixed to a shaft 116, and a control or throttle lever 117 is also fixed to the shaft 116 for effecting movement of the fulcrum element in the slots 111 and 111a. As in the previously described modification, the positions of the two relays are reversed so that while the fulcrum element is moving in the cam portion of one slot it also is moving in the ineffective portion of the other slot. It will be apparent that the operation of the apparatus shown in Fig. 8 is the same as that of the previously described modification. Hence, further description is deemed unnecessary.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. The combination with prime mover apparatus including an ahead section and an astern section, of first and second conduit means for conveying motive fluid to the ahead and astern sections respectively; first and second valves in the first and second conduit means respectively for controlling the flow of motive fluid there-through; first and second relays for controlling the operation of the first and second valves respectively; each of the relays comprising a secondary element connected to its respective valve for opening and closing the latter, a primary element movable to regulate the application of an operating force to the secondary element, a follow-up lever connecting the valve and primary element for moving the latter back to neutral position upon movement of the valve and having thereon a cam surface extending longitudinally thereof, and a fulcrum element movable along the cam surface from a mid-position thereon corresponding to the cut-off position of its respective valve toward one end of the cam surface for effecting movement of the primary element in a direction to open its respective valve, and movable along the cam surface from such mid-position toward the other end of the cam surface without effecting movement of its respective primary element toward valve-opening position; and mechanism for simultaneously moving the fulcrum elements of both the first and second relays along their respective surfaces in such a manner that as one fulcrum element moves from its mid-position in a direction to open its respective valve the other fulcrum element moves from its mid-position in a direction to maintain its respective valve closed.

2. Apparatus according to claim 1 wherein the cam surfaces comprise sides of slots extending longitudinally of their respective follow-up levers, and the fulcrum elements are disposed within their respective slots and are moved longitudinally thereof to effect the desired operation of the valves.

3. Apparatus according to claim 1 wherein each cam surface and its cooperating fulcrum element are disposed between their respective primary element and valve.

4. Apparatus according to claim 1 wherein each cam surface and its cooperating fulcrum element are disposed at the side of their respec-

tive primary element which is opposite to the valve.

5. Apparatus according to claim 1 wherein each fulcrum element is carried by the outer end 5 of a separate lever arm, and the two lever arms are connected together by means of a link for operation in unison.

6. Apparatus according to claim 1 wherein both fulcrum elements are carried by the outer 10 ends of lever arms connected to a single shaft for operation in unison.

7. Apparatus according to claim 1 wherein each of the relays is operated by oil under pressure, and is so positioned with respect to its 15 respective valve to prevent oil leaking therefrom from contacting with the valve so as to cause a fire.

8. The combination with an elastic fluid prime mover apparatus for use as a ship propelling 20 means including a drive shaft and a propeller operatively connected to said drive shaft; of a conduit for conveying motive fluid to such apparatus; a valve for controlling the flow of motive fluid through such conduit; a relay for operating said valve comprising a secondary element connected to the valve, a primary element movable to control the application of an operating force to the secondary element, follow-up 25 mechanism connecting the valve and primary element for restoring the primary element to a neutral position upon movement of the valve in either direction; and means providing for movement 30 of the primary element away from its neu-

tral position for effecting movement of the secondary element and valve, said means comprising a movable control member and being so constructed and arranged that equal increments of movement of the control member effect equal changes in the speed of the ship. 5

9. The combination with an elastic fluid prime mover apparatus for use as a ship propelling means including a drive shaft and a propeller operatively connected to said drive shaft; of a 10 conduit for conveying motive fluid to such apparatus; a valve for controlling the flow of motive fluid through such conduit; a relay for operating said valve comprising a secondary element connected to the valve a primary element 15 movable to control the application of an operating force to the secondary element, and a follow-up lever connecting the valve and primary element for returning the latter to a neutral position upon movement of the valve in either direction and including a fulcrum element; the follow-up lever having thereon a longitudinally disposed cam surface and the fulcrum element being movable along the cam surface to impart movement to the primary element away from its 20 neutral position so as to effect movement of the secondary element and valve; a control member for moving the fulcrum element along the cam surface; the cam surface being so shaped that equal increments of movement of the control 25 member effect operation of the valve so as to cause equal changes in the speed of the ship. 30

HENRY J. HANZLIK.
